UNITED STATES PATENT OFFICE

ARTHUR PFORTNER, OF ROSEDALE, NEW YORK, ASSIGNOR TO IDEAL PERMANENT WAVE PRODUCTS, INC., OF ROSEDALE, LONG ISLAND, NEW YORK, A CORPORATION OF NEW YORK

HAIR CURLING APPARATUS

Application filed March 27, 1931. Serial No. 525,675.

This invention relates to hair curling apparatus; more particularly to artificially heated units for curling hair and imparting thereto so-called permanent waves.

In hair curling apparatus, as known to me, there are utilized artificially heated units, preferably and conveniently heated by electrical resistance elements which are applied by surrounding the electric unit about a strand of hair which has been suitably mounted upon some support. In connection with this hair heating process, different chemical preparations are used for two distinct treatments; one is called a dry wind process and the other a wet wind process. In connection with the dry wind process, the heating units which are used are the so called open type heaters, and the preparation applied to the hair or used in connection with the heat that is applied, is allowed to diffuse under the heat treatment. Under the so-called wet wind process, the preparation used in connection with the hair and the heat that is applied thereto, is preferably under conditions which do not permit the diffusion of the chemical preparation. Such type of heating elements are known as closed heaters.

I have found it desirable, and in accordance with my invention, it is proposed by me to provide apparatus whereby in the process of heating hair to impart the permanent wave, the dry wind type of treatment or the wet wind type of treatment may be combined or alternated in connection with heating elements utilized. It is further contemplated by my invention to provide a hair curling apparatus, including an artificially heated tube, to surround the hair strand as prepared and ready for setting a so-called permanent wave, which may be utilized for a dry wind preparation or a wet wind preparation.

It is a further object of my invention to provide a hair curling apparatus in the nature of an artificially heated tube which may be positioned about properly mounted strands of hair, for heating the same, the hair curling heater thus provided being capable of being used as an open type tube, where a so-called dry wind treatment of the

hair is utilized, or may be used as a closed tube, where a wet wind treatment of the hair is the basis of the process employed.

It is further contemplated by me to provide a hair curling apparatus in the nature 55 of an electrically heated tube, which includes means to optionally either maintain the tube open during the time that the tube is applied to the strand of hair for setting the same, or maintain it closed, depending upon the preparations employed in connection with the process of imparting a so-called permanent 60 wave to hair. Thus by my invention, an electrically heated tube that is used for imparting permanent waves to hair may be 65 changed to a closed type of heater, or an open type of heater, or alternated from one to the other at will, with various degrees of the open position, whereby the heater may be used in connection with diffusible chemical 70 preparations used in connection with the hair which are desired to escape or be volatilized during the heating process, or whereby those preparations or compositions which are desired to be retained in proximity to the 75 strand of hair treated may be so maintained by keeping the tube closed, or the tube may further be varied permitting variation from 80 one process to the other, or combinations thereof.

Further objects of my invention reside in the provision of a hair curling apparatus which has a multiplicity of uses and which may be quickly and conveniently employed by beauticians in connection with treating 85 the hair for effecting the so-called permanent waving of the hair.

To obtain these objects and such further objects as may appear herein, or be herein-after pointed out, I make reference to the 90 accompanying drawing, forming a part hereof, in which;

Figure 1 is a perspective view of my device, with one element removed to show the details of construction;

Figure 2 is a fragmentary sectional view, with the tube valving element in the open position;

Figure 3 is a view similar to Fig. 2, with the valving element in the closed position; 100

Figure 4 is a plan view of the device with the valving element in the open position.

Making reference to the drawing, I have illustrated a single heater of a hair curling apparatus used for imparting a so-called permanent wave to hair. The illustration is in connection with heating units generally employed in numbers sufficient to treat all the hair of the scalp of an individual at one operation so that from 30 to 40 of these units are utilized for one treatment.

In the drawing, the single unit comprises a tube 10 which is open at its bottom 11, and having adjacent a length thereof, a casing 12, within which there is contained the heating element 13. This heating element comprises the standard form of construction, usually several windings of resistance wire such as nichrome wire, which when submitted to electrical energy heats up. Sufficient number of windings are employed, properly insulated from each other by sheets of mica or similar heat resisting and electrical insulating material. A number of strands of heat resisting material are employed to give the proper amount of heating, in accordance with the desired process.

The tube 10, as illustrated, is open at the end 14. Adjacent this end, I provide a valving element generally indicated at 15. This comprises a collar 16, having a screw threaded portion 17 fitting snugly adjacent the end 14 previously described. Interiorly of the collar 16, there is provided an extension portion 18 carrying side arms 19 and 20. A ball member 21 is pivotally mounted between the arms 19 and 20 upon the pins 22 and 23 respectively. This ball member is preferably flattened adjacent the sides 24 and 25 to permit free and easy rotation about the arms 19 and 20.

The movement of the ball member thus described is limited within an angle substantially of 90° and for this purpose a spring wire member 26 is provided, having one end thereof 27 anchored by the set screw 28 passing through the extension 18 and the side wall of the tube 10, previously described. The opposite end 29 of the spring member 26 is anchored in the side wall 25 of the ball member 21. To the upper portion of the ball member 21 there is affixed an actuating finger 30. The ball member is also orificed diametrically at 31. In the position as shown, the spring member 26 is so formed that it will in the dead center position thereof, at one extreme, serve to hold the ball member with the orifice 31 aligned with the opening 14 of the tubular member 10. When in this position, a cap 32 is positioned over the ball member and the assembly therefor thus described, so that it encases this assembly. The lower end of the cap is screw threaded at 33 and engages the screw threaded portion of the collar 16. The cap 32 is preferably formed with

an inwardly directed neck 34 and is orificed at 35. This orifice is slightly smaller than the ball member 21. The side walls of the orifice 35 are such that a 90° portion of the ball member 21 will serve to bring the opening of the orifice 31 all within the neck portion 34 of the cap 32. The walls of the orifice 35 also serve as stops or abutments for the finger member 30 and in this manner, as shown in the dotted positions, serve to either hold the ball member in the fully opened position or in the fully closed position. The spring member 26 also serves to quickly move the ball member either to the fully opened position or to the fully closed position once it has been started from the dead center position. Thus, if the finger member 30 is used to move the ball member 21 in a counterclockwise direction, this movement will be against the spring pressure of the spring 26 until about 90° of movement has been obtained, when the spring pressure will tend to continue the movement of the ball member 21 towards the second dead center position to the right hand side of the pivots 22.

By this construction the valving member is provided over the end 14 of the tube 10, whereby the tubular heating member 10 may be maintained fully opened with the orifice 31 in alignment with the tubular member 10, or this heating tube 10 may be maintained closed by turning the ball member to the position shown in Figure 3, in which position the orifice 31 is arranged transversely to the tube 10.

In the preferred embodiment as illustrated, the valving member may be moved quickly and rapidly from a position leaving the tube 10 fully open, or to a position, fully closing the end of the tube 10. The open position is found desirable when the hair curler is to be used with a so-called dry wind treatment of the hair for imparting a permanent wave. This dry wind treatment comprises using a preparation probably including an ammonia solution in which, it is desirable that during the heating process, the fumes escape while the shrinking of the hair takes place. Where a wet wind process is employed which includes applying the chemical preparation upon the hair itself, and which preparation includes oil constituents together with a starch material, soda, borax, and other such materials. In this latter treatment it is desirable that the tube be closed in order that the vaporous materials be maintained in contact with the hair and for other purposes which those skilled in the art will readily appreciate.

Thus the beautician may determine from the appearance, texture and general characteristics of the hair to be treated whether the dry wind process or the wet wind process may be most effectively employed. Without use of other apparatus, the treatment may be

applied, adjusting the heating tubes in accordance with whether quick diffusion of the preparation is found desirable and thereby adjusting the heaters to the open position, or whether slow diffusion or no diffusion is desired, in which event the valving element previously described is moved either to the fully closed position or partially closed position. It will be understood that adjustment may be made by the spring element or frictional element to hold the ball member 21 not only in the extreme open or closed positions, but at intermediate positions. Thus, variable atmospheric pressure may be maintained within the tube 10 and the products resulting from the heating treatment may be either permitted to circulate from contact with the hair which is undergoing the treatment, and pass off into the atmosphere directly, or they may be maintained in contact with the hair. Also, the degree of circulation of these vaporized products, or the heat generated by the heater in connection with the vaporized products may be controlled within limits by the degree of circulation resulting from controlling the opening of the valving member 15.

The valving assembly 15 as heretofore described has not been emphasized as to the material from which it is made, and though this may be made of metal, it is preferred that some non-metallic material be employed, such as hard rubber, bakelite, or wood. Thus, the heating members may be more readily handled without danger of scorching the hand during the time that the current is on, and serves to heat the heating elements.

In general, it will be observed that I have provided a hair curling apparatus which not only serves a dual purpose in a single apparatus of both an open type and a closed type tube, but variations or combinations of the processes of treating the hair may be employed by the apparatus provided.

Having thus described my invention and illustrated its use, what I claim as new and desire to secure by Letters Patent, is:—

1. In a hair curling device, a heater tube comprising a hair engaging section and a spring guided valving element at its opposite end.

2. In a hair curling device, a heater tube, including a hair engaging section, and means at its opposite end for optionally maintaining the tube opened or closed, the opening or closing operation being spring guided, whereby each position may be assumed quickly.

3. In a hair curling apparatus, a heater tube, a hair engaging section, a heating element adjacent said section, means opposite to the hair engaging section for permitting the vaporous products to pass off to the atmosphere, and a spring operable valving ele-

ment adjacent said end for limiting the passage open to the atmosphere.

4. In a hair curling apparatus, a heater tube, a hair engaging section, means to heat said section, an opening in said tube through which vaporous products may pass at an end opposite to the hair engaging section, a valving member disposed across said opening, means for pivotally mounting said valving member, and means for mounting said valving member in open or closed position over said opening, said pivotal mounting including spring actuation to either the open or closed position of said valving member.

5. In a hair curling device, a heater tube, a hair engaging section, means for heating said section, means opposite to said section formed at the extreme end of said tube permitting the escape of the vaporous products, a tube engaging assembly over said opening, said assembly, including valve mounting means, and valve closing means, and means for mounting said valve in the open or closed position, and means for actuating said valve to the open or closed position, comprising a resilient member urging said valve to the extreme open or closed position.

6. A hair curling device, comprising a heater tube, a hair engaging section at one end, heating means adjacent said hair engaging section, an opening in said tube oppositely disposed to the heating means whereby the vaporous products may circulate outwardly from the interior of said tube, a valving member over said opening, comprising a ball member, said ball member being orificed whereby it may be aligned with the aforesaid vapor tube opening, means for pivotally mounting said ball member, said ball member cooperating with said tube and a cap member to maintain said heater tube open or closed, and means for actuating said ball member to the open or closed position.

7. A hair curling device, comprising a heater tube, a hair engaging section, including heating means adjacent one end of said tube, an opening for said tube at the opposite end, whereby vaporous products may circulate from the interior of said tube, means for controlling and varying said opening, said last mentioned means comprising a valving element, and means for actuating said element and hold the same to the open or closed position, comprising a resilient spring.

8. For use with a hair curling device, comprising a heater tube and including means for heating said tube, said tube having an opening to permit the escape of vaporous products resulting from heating said tube when used in connection with a hair treating preparation, of a valving assembly for said opening, comprising a tube engaging portion and a movable valving member, and means for actuating said valving member to the open or closed position, comprising a resil-

ient spring member whereby said opening may be optionally restricted in size or opened to permit escape of the vaporous products of said tube.

9: For use with a hair curling device, comprising a heater tube and including means for heating said tube, said tube having an opening to permit the escape of vaporous products resulting from heating said tube when used in connection with a hair treating preparation, of a valving assembly for said opening, comprising a tube engaging portion and a movable pivotally mounted valving member, and means for actuating said valving member to the open or closed position, comprising a resilient spring member, said spring member engaging said valving member in an off-center position in respect to the pivotal mounting whereby the valving member may be held to the open or closed position.

In witness whereof I have hereunto signed my name this 11th day of March, 1931.

ARTHUR PFORTNER.
